DESIGN FOR A SWINGING TARGET GAME DEVICE

August C. Trombley, Washington, D. C., assignor
of seven-tenths to Harry Naiman, Washington,
D. C.

Application July 22, 1940, Serial No. 93,844

Term of patent 3½ years

To all whom it may concern:

Be it known that I, August C. Trombley, a citizen of the United States, residing at Washington, in the District of Columbia, have invented a new, original, and ornamental Design for a Swinging Target Game Device, of which the following is a specification, reference being had to the accompanying drawing, forming part thereof.

Figure 1 is a front elevation of a swinging target game device, showing my new design.

Figure 2 is a side elevation thereof.

The back is plain.

I claim:

The ornamental design for a swinging target game device, as shown and described.

AUGUST C. TROMBLEY.
